UNITED STATES PATENT OFFICE

154,323

DESIGN FOR A CHILD'S TEETER

James H. Reed, Detroit, Mich.

Application February 27, 1948, Serial No. 144,792

Term of patent 7 years

(Cl. D34—15)

To all whom it may concern:

Be it known that I, James H. Reed, a citizen of the United States residing at Detroit, in the county of Wayne and State of Michigan, have invented a new, original, and ornamental Design for a Child's Teeter, of which the following is a specification, reference being had to the accompanying drawing, forming part thereof.

In the drawing:

The figure is a perspective view of a child's teeter, showing my new design.

I claim:

The ornamental design for a child's teeter, as shown.

JAMES H. REED.
